UNITED STATES PATENT OFFICE.

AARON FISHMAN, OF CHICAGO, ILLINOIS.

DESIGN FOR A CABINET.

Application filed July 21, 1926. Serial No. 18,430. Term of patent 14 years.

To all whom it may concern:

Be it known that I, AARON FISHMAN, a citizen of the United States, and a resident of Chicago, county of Cook, State of Illinois, have invented a new, original, and ornamental Design for Cabinets, of which the following is a specification, reference being had to the accompanying drawing, forming part thereof.

The figure is a perspective view of the cabinet with the lid closed showing my new design.

The cabinet may be adapted for holding various articles, for instance, table silverware, toilet articles, and the like.

I claim:

The ornamental design for a cabinet, substantially as shown.

AARON FISHMAN.
